UNITED STATES PATENT OFFICE.

JOSEPH B. CRANE, OF PITTSBURGH, PENNSYLVANIA, ASSIGNOR TO INTERNATIONAL COMBUSTION ENGINEERING CORPORATION, OF NEW YORK, N. Y., A CORPORATION OF DELAWARE.

CONTROL OF GASES THROUGH BOILERS.

Application filed October 24, 1923. Serial No. 670,490.

Although a considerable percentage of heat generated in the furnace of a boiler is transmitted to the heating surface by radiation from the hot surfaces of the furnace and the fuel bed, the efficiency of a boiler depends principally on the heat imparted to the heating surfaces by convection, i. e., the contact of hot gaseous particles of gas with the heating surfaces, and the greater the number of such particles in a stream of gas caused to contact with the heating surface in a unit, the higher the efficiency attained. Hence, a high velocity or rate of flow is desirable. With a given rate of flow it is evident that the number of hot particles of gas brought into contact with a heating surface will be dependent on the length of such surfaces and also the cross section of each elementary stream of gas traversing the heating surfaces. It is known that in streams of hot gases passing along a heat absorbing surface, there will be a diffusive action, i. e., a movement of the hot particles to and from the absorbing surfaces. The length of a portion of a furnace and this back and forth movement of the hot particles is dependent on the cross section or mean hydraulic depth of the streams of gas, and hence the smaller this cross section or mean hydraulic depth the greater the proportion of hot particles of gas which will contact with the heat absorbing surfaces.

In the manufacture of water tube boilers, the ends of the tubes are secured in holes formed in the drums or headers and these holes must be spaced such distances apart as not detrimentally to weaken the drums or headers as against internal pressures. This necessary spacing of the tubes permits of the passage of streams of hot gases of such large cross section or hydraulic mean depth that a very large percentage of the hot particles will either not contact with the surfaces of the tubes at all or so infrequently in passing through the boiler that the gases entering the stack will have a very high temperature. In Fig. 1 I have illustrated my invention in connection with a vertical water tube boiler and have shown a fragmentary portion of the combustion chamber and boiler setting in order to indicate the relation of the boiler to different parts of the furnace.

The combustion chamber A of any well known form has the grate 8 in the lower part thereof, and the lower drum 9 of the boiler is adjacent the bridge wall 10. The rear wall of the furnace is indicated fragmentarily at 11, the side wall at 12, and the offtake for the products of combustion is shown at 13. The gaseous products of combustion will flow from the combustion chamber A through the bank of tubes of the boiler and out through the offtake in a well known manner.

The quantity of heat imparted to a boiler by radiation from the hot surfaces of the furnace and the fuel bed is dependent on the difference between the fourth power of the absolute temperature of the hot and cold surfaces, but under the present practice only a comparatively small proportion of the heating surfaces of a boiler, i. e., those immediately adjacent to the combustion chamber, are acted on by the radiant heat, as the hot gases radiate little heat.

The invention described herein has for its object the provision of means whereby the cross section or the hydraulic mean depth is so reduced that the diffusive action of a stream of hot gases may be effective to increase the percentage of hot particles of gas brought into contact with the heating surface of a boiler and also the frequency of contact of the particles with such surfaces. It is a further object of the invention to subject practically all of the tubes to radiant heat. The invention is hereinafter more fully described and claimed.

In the accompanying drawing forming a part of this specification, Fig. 1 is a sectional elevation of a vertical water tube boiler embodying the improvement claimed herein; Fig. 2 is a detail elevation showing two tubes and an interposed wall or partition; Fig. 3 is a sectional elevation on a plane indicated by the line III-III, Fig. 1; Fig. 4 is a sectional view on a plane indicated by the line IV-IV, Fig. 2; Fig. 5 is a sectional plan view on an enlarged scale, the plane of section being indicated by the line V-V, Fig. 1; Fig. 6 is a sectional view on a vertical plane across the tubes of a horizontal water tube boiler showing the arrangement of the wall or partition when the tubes are arranged in staggered relation; and Fig. 7 is a similar view showing

the arrangement of the walls or partitions when the tubes are arranged in vertical alinement.

In the practice of the invention walls or partitions 1 formed of refractory material such as asbestos board, are arranged between adjacent tubes or rows and in the case of boilers having upper and lower drums and connecting tubes or banks of tubes, the walls 10 or partitions extend vertically from drum to drum. In order that these partitions may not shield the tubes adjacent to the fuel bed from the radiant heat from the fuel bed and the walls of the combustion chamber or furnace these partitions will extend horizontally 15 from the third or fourth front row of tubes backward for the entire depth of the boiler. These walls or partitions are made of a thickness less than the spaces between adjacent tubes or adjacent lines of tubes proportional 20 to the desired thickness of the streams of hot gases flowing from the combustion chamber and are spaced equal distances from adjacent tubes. These walls can be conveniently 25 formed in horizontal sections and held in alinement and away from the tubes by blocks 2 having grooved faces to fit around the tubes and connected by webs 3 intermediate the ends of the blocks. As shown in 30 Fig. 4 these H-shaped pieces engage the edges of adjacent sections of the walls and also bear on adjacent tubes.

In order to prevent a short circuiting of the gases, whereby the upper portions of the 35 tubes will not be efficiently heated, the walls or partitions are made tapering from their lower ends, as shown in Fig. 4, so that the vertical spaces between adjacent walls or partitions will be progressively larger from 40 the lower portions of the tubes upward, thus ensuring an equal or approximately equal flow of gases towards the stack at all points between the drums.

As shown in Figs. 6 and 7, the improvement claimed herein may be embodied in 45 boilers having their water tubes arranged horizontally or approximately so. In some types of this class of boilers, the tubes are arranged in staggered relation vertically, as 50 shown in Fig. 8, in which case the walls or partitions would be arranged at an angle to the side walls 7 of the boiler setting, as shown, and hence if the partition were extended so that an end would abut against 55 a side wall or walls, it would prevent hot gases from access to tubes above or below such partition. As for example, if the partition 1^a should be extended further downwards, it would prevent hot gases from flowing 60 to and around tubes above and to the left of said partition. Similarly, if the partitions 1^b should be extended upwards to the side wall of the setting, there would not be any circulation of gases entering the bank 65 of tubes below and at the right of partition

1^b. Such gases would be simply pocketed. In order to ensure the flow of gases around all of the tubes, those partitions which if extended so that their ends would contact with a side wall or come into such proximity thereto as to prevent ample flow to and around tubes adjacent to the side walls of the setting, are stopped off as shown in Fig. 8. 70

When, however, the tubes are arranged in alinement vertically, as shown in Fig. 7, the partitions would be arranged vertically between adjacent rows of the tubes. 75

It will be readily understood by those skilled in the art that as the streams of gas can be made very thin or small in cross section, the percentage of hot particles of gas brought into contact with the tubes by the diffusive action in the streams will be very large. And further, these walls or partitions will be brought to or approximately to 80 the temperature of the gases, and the tubes will be heated by heat radiated from the surfaces of the walls or partitions. 85

The walls or partitions may be so constructed that adjacent walls form passages 90 enclosing a plurality of tubes so that the gases flowing between such adjacent walls are confined laterally and flow in substantial unbroken sheets along opposite sides of 95 the enclosed rows of tubes. 100

I claim herein as my invention:

1. A water tube boiler consisting of a bank of tubes arranged in parallel rows, a combustion chamber and an outlet for products of combustion, said elements being so arranged that the gases will flow in a direction at an angle to the tubes in combination with a plurality of substantially continuous walls or partitions extending between and substantially parallel with adjacent parallel rows of tubes in a direction of the flow of the gases and spaced from the tubes forming the rows, said walls or partitions being substantially continuous through the bank and adapted to divide the gases flowing from the combustion chamber into a plurality of streams laterally confined to operate on a plurality of tubes forming the rows or lines between adjacent walls. 105 110

2. A water tube boiler consisting of upper and lower drums and a bank of tubes arranged in parallel rows connecting said drums in combination with substantially continuous vertical walls or partitions arranged between and substantially parallel with the rows of tubes and spaced from the tubes forming the rows and extending from the lower to the upper drum. 115 120

3. A water tube boiler consisting of upper and lower drums and tubes connecting said drums in combination with vertical walls or partitions arranged between and substantially parallel with the rows of tubes and spaced from the tubes forming the rows and extending from the lower to the upper drum. 125 130

and tapering from their lower ends upwards.

4. In combination, a furnace having a combustion chamber and an outlet for the products of combustion, a water tube boiler having a bank of tubes between the chamber and the outlet, substantially continuous partitions between rows of parallel tubes and spaced from the tubes of the rows, the partitions forming passages in said bank extending substantially in the direction of flow of the gaseous products of combustion.

5. In combination, a furnace having a combustion chamber, a vertical water tube

boiler to the rear of the combustion chamber, the tubes of which are arranged in transverse parallel rows and an outlet beyond the boiler, substantially continuous partitions extending between and longitudinally of the rows of tubes and forming substantially continuous passages transversely of the bank of tubes whereby gases flow through the bank in a direction transverse thereof.

In testimony whereof, I have hereunto set my hand.

JOSEPH B. CRANE.
